TRACTION APPLYING DEVICE FOR SPLINTS

Frank L. Gray, Bridgeport, Conn.

Application December 27, 1937, Serial No. 181,852

5 Claims. (Cl. 128—84)

The present invention relates to a traction device for splints, and is especially intended for use upon a leg splint of the so-called Thomas type. The Thomas splint, which is extensively used in first aid work, consists of an elongated U-shaped frame having a ring secured at the ends of the side bars, and which ring is adapted to be passed over the leg so that it rests snugly against the buttock, the bars being disposed at each side of the leg and the transverse lower end of the splint being spaced below the foot. It has been the practice heretofore in order to obtain traction upon the leg to apply a bandage just above the ankle, the tie ends of the bandage being then knotted about the end of the splint, and thereupon by means of a stick inserted between these tie ends between the ankle bandage and the end of the splint twisting until considerable traction is applied to the leg. It is extremely important in leg fracture cases to manually apply traction to the leg as soon as possible to prevent injurious complications, and thereupon to avoid any contraction until a splint is provided and the traction is applied and maintained by permanent connections with the splint. With the above method considerable difficulty has been experienced in accomplishing this because of the necessity of manually holding the leg, while applying the splint and securing the ankle bandage and traction ties. It has in fact been practically essential to the proper application of the splint, bandages and ties to have at least two persons apply them, one person holding the leg in a manner to apply the traction and engage the splint with it, while the other person prepared and applied the ankle bandage and traction ties.

It is an object of the present invention to provide a traction applying device which will form a permanent part of the splint, and by means of which it is possible to engage the splint with the leg while manually maintaining traction upon it, and thereupon support the ankle in a supporting cradle which carries an ankle band, the ankle band being so arranged that the person applying the traction to the leg may continue to do this with one hand while securing the ankle band with his free hand, and then, after so securing the ankle band, apply traction with said free hand by means of a traction strap connected between the ankle band and the end of the splint, all the while maintaining manual traction with the one hand. In this way it is possible with the present device for one person to apply the splint, with greater facility and speed than has been heretofore possible, and with more comfort

and safety to the patient and with less likelihood of injurious complications due to contraction to the leg after it has first been extended.

It is a further object of the invention to provide such traction device which will be adjustable, so that the splint with the traction device may be applied to different length legs, and further to provide such a device which may be used for either the right or left leg simply by inverting its position upon the splint, it being understood that the Thomas splint is adapted for use upon the right or left leg and for this purpose has one side bar shorter than the other.

A further object is to provide a traction device of simple and inexpensive construction, and which may be applied as an attachment to the present type of Thomas splint, or other splints of substantially the same construction, without the necessity of any alteration to the splint itself.

While the invention is illustrated and described with reference to a leg fracture splint, it will be understood that it may also be applied to an arm splint.

With the above and other objects in view, an embodiment of the invention is shown in the accompanying drawing, and this embodiment will be hereinafter more fully described with reference thereto, and the invention will be finally pointed out in the claims.

In the drawing:

Fig. 1 is a perspective view of a Thomas splint showing the traction applying device according to the present invention applied thereto.

Fig. 2 is a rear elevation of the traction applying device, the ankle band being shown in open position.

Fig. 3 is an end elevation as seen from the left in Fig. 2.

Fig. 4 is a bottom plan view.

Fig. 5 is a perspective view showing the splint applied to the left leg of a patient with the traction applying device secured to the leg and traction applied.

Similar reference characters indicate corresponding parts throughout the several figures of the drawing.

Referring to the drawing the splint illustrated is a so-called Thomas splint, and consists of a U-shape frame having a short inner leg 10, a long outer leg 11, and a notched lower end portion 12, the side legs diverging slightly toward their upper ends, and being rigidly connected at their upper ends to a ring 13, which is preferably padded as shown and which is adapted to be

engaged over the leg to rest firmly against the buttock.

The traction applying device consists of an ankle band 14, preferably formed of a rectangular piece of leather, and to which is secured a pair of spaced supporting cradle straps 15 and 16 in the form of loops, these straps being disposed in parallel relation to the longitudinal edges of the band 14, and having their ends butted along the center line of said band and secured by rivets 17 arranged at each side of said butted ends. These straps 15 and 16 are adapted to be slidably engaged over the side bars of the splint, as shown in Fig. 1, and form a longitudinally adjustable supporting cradle beneath the ankle band, with the upper traverse of each strap directly overlying the lower traverse, and which not only supports the ankle band but provides a cradle support for the leg after the splint has been applied, as will hereinafter more fully appear. The ankle band is preferably faced with a piece of cushioning material, as for instance a piece of sheepskin 18, the wool being exposed and the leather base being secured to the band 14 by stitching 19.

In the space between the bands 15 and 16 there is provided a strap 20 secured centrally to the band 14 by a rivet 21, this strap being provided at one end with a friction buckle 22 the end of which is preferably disposed slightly inwardly of the end of the band 14, and the other end of the strap being extended so that it may be engaged with the friction buckle to secure and tighten the band about the ankle. This buckle may be of any suitable type and as illustrated is provided with a spring pressed gripping and releasing lever 22a.

At each side of the ankle band 14 and substantially along the diametric plane of the band, 40 when it is in its ankle embracing substantially cylindrical form, there are secured the ends of a yoke strap 23 which is of sufficient length to extend around the heel of the patient, the ends of this strap being carried over the strap 20 and 45 being secured at each side of the strap 20 by rivets 24, to thus provide retaining bands in which the strap 20 is slidably engaged at each side so that it is supported in a position where its buckle end and its extended end are held in 50 a position where they may be readily grasped, this arrangement also insuring that the strap 20 will remain substantially centrally of the ankle band, so that when it is tightened it will cause the band to grip evenly and there will be no 55 danger of slippage.

A connecting link member consisting of two integrally connected loops 25 and 26, disposed in planes at right angles to each other, has its loop 25 slidably engaged upon the yoke strap 60 23 so that it is disposed in a vertical plane, while the loop 26 is disposed in a horizontal plane. The loop 26 has secured to it the end of a traction applying strap 27, this strap being carried through the loop 26 and secured by a rivet 28 contiguous to the loop 26, one end of the strap being then carried through the buckle 29 and folded back and riveted at 30 to secure the buckle. The other end of the strap is carried about the notched 65 end 12 of the splint and engaged in the buckle, this buckle being preferably a friction type of buckle similar to the buckle 22, and which holds the strap at any point to which it is pulled, being releasable by means of a spring pressed releasing 70 lever 29a.

The method of applying the splint and traction device according to the invention is as follows:

Assuming that the left leg is fractured, the splint is engaged with the short leg 10 inwardly and with the ankle band of the traction applying device open, as shown in Fig. 1. The person applying the splint passes his hands through the ring 13 and grasps the foot of the patient, the left hand grasping the heel and the right hand holding the foot upright, and then pulls the leg 10 to apply traction. It is important that this initial manually applied traction be maintained until the splint is in place. While still holding the patient's foot he manipulates the splint up the leg, which may be done by first placing the end 15 of the splint in front of one knee, or against the chest, or shoulder, or at a point where one foot can be employed to push it up the leg. It has been found that this operation can easily be accomplished by one man while still holding the patient's foot and maintaining a firm pull on the leg, the foot as above pointed out being held with the left hand grasping the heel and the right hand holding the foot upright. When the splint has 20 been fully engaged, with the ring 13 resting firmly against the buttock the ankle is laid upon the open ankle band 14, whereupon the supporting bands 15 and 16 support the weight of the ankle as a cradle. At this point the person applying the splint, while still maintaining traction upon the leg with the left hand, which is grasping the patient's heel, removes his right hand from the foot and employs it to engage the end of the strap 20 through the buckle 22, thereupon closing the ankle band about the leg slightly 25 above the ankle, the strap being then tightened so that the band is firmly secured about the ankle. This operation, as above pointed out, is 30 accomplished while still maintaining traction upon the leg with the left hand. When the ankle band is thus secured the free right hand is then employed to apply traction by grasping the end of the strap 27 and pulling upon it, whereupon the ankle band is pulled by means of the yoke strap 23, as shown in Fig. 5. At this point 35 the traction is all taken by the splint, and the person applying the splint may remove his left hand from the patient's foot. It will be noted that in the tightened position of the device the yoke strap 23 firmly engages the sides of the 40 patient's heel and thus supports the foot upright so that there is no chance of its turning and moving the fractured leg bones. With the traction thus positively and securely applied to the 45 leg, and with the leg supported by the cradle 50 straps 15 and 16, further bandages may be applied in the usual manner to the leg, as required. The positive manner in which the device maintains traction insures, during transportation of the patient from the scene of the accident to the 55 home or hospital, that no complications will ensue, because of loosening of the band or loss of traction, due to slippage. As no particular skill is required in applying the ankle band and securing traction, such as has been necessary with the previous method of forming an ankle band from bandage, the device may be applied by persons having very little practice, and with the assurance that the patient will not suffer either 60 because of failure of the splint or lack of skill 65 on the part of the person applying the splint.

I have illustrated and described preferred and satisfactory embodiment of the invention, but it will be understood that changes may be made 70

therein within the spirit and scope thereof as defined in the appended claims.

Having thus described my invention what I claim and desire to secure by Letters Patent is:

FRANK L. GRAY. 85
